BOTTLE-HOLDING INFANT JACKET

Connie A. Palomares, 15240 Kittridge, No. 312,
Van Nuys, Calif. 91405

Filed June 29, 1972, Ser. No. 267,368

Term of patent 14 years

Int. Cl. D2—05

U.S. Cl. D2—229

FIG. 1 is a perspective view of a bottle-holding infant jacket showing my new design;

FIG. 2 is a rear elevational view thereof;

FIG. 3 is an end elevational view taken in the direction of the arrow 3;

FIG. 4 is a top plan view; and

FIG. 5 is a bottom plan view.

I claim:

The ornamental design for a bottle-holding infant jacket, substantially as shown.
